Primary Examiner — Jonathan J Han*Assistant Examiner* — Christen Pilar Brown(74) *Attorney, Agent, or Firm* — Kunzler Bean & Adamson, PC; Michael Bartholomew(57) **CLAIM**

The ornamental design for a shoe, as shown and described.

DESCRIPTION

FIG. 1 is a front, right and top perspective view of a shoe, showing my design.

FIG. 2 is a rear, left and bottom perspective view thereof.

FIG. 3 is a top plan view thereof.

FIG. 4 is a bottom plan view thereof.

FIG. 5 is a left side elevation view thereof.

FIG. 6 is a right side elevation view thereof.

FIG. 7 is a rear elevation view thereof.

FIG. 8 is a front elevation view thereof.

FIG. 9 is an enlarged view of the area labeled "9" in FIG. 2; and,

FIG. 10 is an enlarged view of the area labeled "10" in FIG. 8.

The shoe for the right foot is a mirror image of the shoe for the left foot as shown in FIGS. 1 to 10 and is also claimed. The broken lines depict portions of the shoe that form no part of the claimed design.

The dot-dash lines in FIGS. 2, 8, 9, and 10 are for the purpose of showing the areas of enlargement and form no part of the claimed design.
